UNITED STATES PATENT OFFICE.

WILLIAM KELSO AND JOSEPH KELSO, OF PITTSBURGH, PENNSYLVANIA, ASSIGNEES
TO THE McCONWAY & TORLEY COMPANY, OF PITTSBURGH, PENNSYLVANIA, A
CORPORATION OF PENNSYLVANIA.

DRAFT APPLIANCE FOR RAILWAY-VEHICLES.

1,346,545.

Specification of Letters Patent. Patented July 13, 1920.

Application filed March 30, 1920. Serial No. 369,933.

To all whom it may concern:

Be it known that we, WILLIAM KELSO and JOSEPH KELSO, citizens of the United States, residing at Pittsburgh, in the county of Allegheny and State of Pennsylvania, have invented certain new and useful Improvements in Draft Appliances for Railway-Vehicles; and we do hereby declare the following to be a full, clear, and exact description of the invention, such as will enable others skilled in the art to which it appertains to make and use the same.

Our invention relates to the construction of draft appliances for railway vehicles and particularly to that class of car couplers in which the coupler head is pivotally mounted upon the coupler stem and wherein the latter is designed to be attached to the railway vehicle in such manner as to be capable of a lateral swinging movement. The primary object of the invention is to provide a coupler of this type with simple and durable means for efficiently centralizing the coupler head with respect to the coupler stem and for centralizing the coupler stem with respect to the body of the car or other railway vehicle upon which the coupler is mounted. A further object of the invention is so to construct and combine the several elements of the mechanism that they may be readily assembled and disassembled, thereby facilitating the renewal of any parts which may be worn out or damaged in service.

In the drawings illustrating the best form in which we contemplate applying the principle of our invention, the scope whereof is pointed out in the claims,—

Figure 1 is a view, partly in plan and partly in horizontal section, of a car coupler embodying the invention, the adjacent portion of a car underframe being also shown in order to exhibit the relation of the coupler thereto.

Fig. 2 is a side elevation of the car coupler illustrated in Fig. 1, the forward end of the coupler head being broken away.

Fig. 3 is a horizontal sectional view of the coupler in a laterally displaced position showing the relations assumed by the parts and also illustrating the neighboring portions of the car underframe.

Fig. 4 is a vertical central section of the coupler.

Fig. 5 is a transverse section on the line 5—5, Fig. 1.

In the drawings, 1 indicates the stem of the coupler and 2 is the coupler head. The coupler head is pivotally mounted upon the forward end of the coupler stem, preferably by means of a vertically extending pivot pin 3 which, as shown, may conveniently be inserted from below so as to be downwardly removable. As a means for permitting the coupler to be attached to a railway vehicle so as to swing laterally with respect thereto, the coupler stem is preferably provided near its rear end with a pivot pin opening 4 which is adapted to receive the usual tail pin (not shown) commonly employed to connect the coupler to the draft rigging. The coupler stem, which is of bifurcated form, may be constructed of upper and lower similar plates or bar members 5 between the rear ends of which a spacer 6 is interposed. The plate members 5 and the intervening spacer 6 are rigidly secured together by a rivet 8, and the forward ends of these plates may also be united by a rivet 9. At their forward ends the plates 5 are provided with suitable aligned pivot pin openings 10 for the reception of the pivot pin 3.

The coupler rests upon a carry iron 11 which may be attached to the center sills or draft sills of the car in any usual or preferred way.

Mounted between the upper and lower bars or plates 5 so as to be capable of reciprocating in the direction of length of the coupler stem 1, is a slide 13 which is preferably fashioned as a unitary frame having on its opposite sides upper and lower guide flanges 14 between which the corresponding plates 5 of the coupler stem are received. The forward end of the slideable frame 13 is provided on opposite sides of the pivot pin 3 with shoulders or abutments 15 which are adapted to engage and coöperate with correspondingly disposed shoulders 16 upon the coupler head 2. When, as illustrated in Fig. 3, the coupler head swings with respect to the coupler stem 1, one or the other of the abutments 16, depending upon the direction in

which the coupler head turns, presses upon the neighboring abutment 15 of the slide 13 and thus forces the latter rearwardly. The rear end of the slide 13 bears against a follower 17 which, in turn, is seated upon the forward end of a longitudinally extending spring 18 whose other end abuts the filler block or spacer member 6 of the coupler stem. It will thus be seen that the rearward movement of the slide 13 induced by a rotation of the coupler head 2 upon its pivot pin 3 causes a corresponding rearward movement of the follower 17 and results in compressing the spring 18. As soon as the force causing the lateral displacement of the coupler head from its normal or centralized position ceases to act, the spring 18 will expand, thereby forcing the follower 17 and slide 13 forwardly and restoring the coupler head to its centralized position with respect to the coupler stem, as illustrated in Fig. 1.

The follower 17 is preferably provided on its rear face with a projection or lug 19 for maintaining the spring 18 in position, and the forward end of the spacer 6 of the coupler stem is also preferably provided with flanges 20 for a similar purpose. As will hereinafter appear, the follower 17 when functioning in the centralization of the coupler stem with respect to the car has a reciprocating movement relative to the slidable frame 13. In order to insure that the follower shall perform this sliding movement without binding it is preferred to provide it with longitudinally extending guides 21 which are adapted to engage and have extended contact with the upper and lower plates 5 of the coupler stem and also with the inner faces of the guide flanges 14 of the slidable frame. By extending the guides 21 rearwardly a sufficient distance so that they will come in contact with the forward end of the filler member 6 of the coupler stem when the spring 18 has reached any desired limit of compression, injury to the spring due to over compression may be prevented.

The slidable member 13, which for the sake of lightness may conveniently be made of skeleton form and bifurcated at its rear end, is provided with an elongated slot 22 affording clearance for the rivet 9 and also preferably has a vertically extending post or column 23 tying its upper and lower portions together. Pivottally mounted upon opposite sides of the slide 13 near its rear end, as for example by means of pivot pins 24 fashioned as rivets, is a pair of overlapping independently rotatable bell-crank levers 25 whose adjacent shorter arms 26 are adapted to engage and actuate the follower 17, the outer ends of their forwardly extending longer arms 27 being adapted to contact the center sills or draft sills 12 or other suitable portion of the car. Being mounted upon the slide 13 the pivotal points or pivotal axes of

the levers 25 partake of the movement of the slide when the latter reciprocates upon the coupler stem 1 in response to movements of the coupler head 2, the levers thus floating with the slide and being always ready, in the normal position of the coupler, to act upon the follower 17 without lost motion to effect a compression of the spring 18 upon the coupler being displaced laterally from its centralized position. 7

The operation of the mechanism in centralizing the coupler stem 1 with respect to the car will be readily understood from Figs. 1 and 3 of the drawings. When the coupler is in its normal position in the longitudinal axis of the car, as illustrated in Fig. 1, the forwardly extending long arms 27 of the levers 25 are held in contact with the center sills or draft sills 12 by the pressure of the spring 18 acting through the intermediacy of the follower 17. When the car passes around a curve in the track the coupler swings or is displaced laterally from its normal position. This displacement of the stem 1 of the coupler causes, as shown in Fig. 3, one or the other of the levers 25, depending upon the direction in which the coupler swings, to turn upon its pivot pin 24 and force the follower 17 rearwardly, thus effecting a compression of the spring 18 corresponding to the extent of lateral displacement of the coupler stem. Upon the withdrawal of the force causing the stem of the coupler to be displaced from its normal position in the longitudinal axis of the car, the expansion of the spring 18, operating through the follower 17 and the lever 25 which has actuated the follower, restores the coupler stem to centralized position. It will be understood of course that the operations of centering the coupler stem with respect to the car and of centering the coupler head with respect to the stem, although they have been herein separately described, may and usually do occur simultaneously. 95

We claim:—

1. In a railway draft appliance, the combination with a coupler having a head and stem and which is adapted to be connected to a railway vehicle so as to swing laterally with respect thereto, of means mounted on said stem for normally maintaining the latter in centralized position, said means involving a spring mounted upon and extending in the direction of length of said stem, and a plurality of independently movable levers pivotally mounted upon opposite sides of the longitudinal axis of said stem and each adapted to energize said spring. 115

2. In a railway draft appliance, the combination with a coupler having a head and stem and which is adapted to be connected to a railway vehicle so as to swing laterally with respect thereto, of means mounted on said stem for normally maintaining the lat- 125

ter in centralized position, said means involving a spring, and a plurality of pivotally mounted members having spaced pivotal axes and each adapted independently to energize said spring.

3. In a railway draft appliance, the combination with a coupler having a head and stem and which is adapted to be connected to a railway vehicle so as to swing laterally with respect thereto, of means mounted on said stem for normally maintaining the latter in centralized position, said means involving a spring, a follower adapted to energize said spring, and a plurality of pivotally mounted members having spaced pivotal axes and each adapted independently to energize said spring.

4. In a railway draft appliance, the combination with a coupler stem which is adapted to be connected to a railway vehicle so as to swing laterally with respect thereto, of a coupler head pivotally connected to said stem, means for centralizing said stem with respect to the railway vehicle, and means for centralizing said head with respect to said stem, each of said means involving in common a spring and a follower which is movable to energize said spring when said stem is displaced laterally in either direction from its centralized position and also when said head is displaced laterally in either direction from its normal position with respect to said stem.

5. In a railway draft appliance, the combination with a coupler stem which is adapted to be connected to a railway vehicle so as to swing laterally with respect thereto, of a coupler head pivotally connected to said stem, means for centralizing said stem with respect to the railway vehicle, and means for centralizing said head with respect to said stem, each of said means involving in common a spring extending in the direction of length of said stem and a follower which is movable to energize said spring when said stem is displaced laterally from its centralized position and also when said head is displaced laterally with respect to said stem.

6. In a railway draft appliance, the combination with a coupler stem which is adapted to be connected to a railway vehicle so as to swing laterally with respect thereto, of a coupler head pivotally connected to said stem, a spring mounted upon said stem, means engaging and adapted to move one end of said spring to energize the same when said stem is displaced laterally in either direction from its centralized position, and means engaging and adapted to move said

end of said spring to energize the same when said head is displaced laterally in either direction with respect to said stem.

7. In a railway draft appliance, the combination with a coupler stem which is adapted to be connected to a railway vehicle so as to swing laterally with respect thereto, of a coupler head pivotally connected to said stem, a spring mounted upon said stem, a slide mounted on said stem and adapted to be actuated to cause said spring to be energized upon a pivotal movement of said head with respect to said stem, and lever mechanism carried by said slide and adapted to cause said spring to be energized when said stem is displaced laterally from its centralized position.

8. In a railway draft appliance, the combination with a coupler stem which is adapted to be connected to a railway vehicle so as to swing laterally with respect thereto, of a coupler head pivotally mounted upon said stem, a spring mounted on said stem, a slide mounted to reciprocate longitudinally on said stem and adapted to be actuated when said head is displaced from its centralized position with respect to said stem, and a plurality of levers mounted upon said slide and adapted to be actuated to cause a compression of said spring when said stem is displaced laterally from its centralized position.

9. In a railway draft appliance, the combination with a coupler stem which is adapted to be connected to a railway vehicle so as to swing laterally with respect thereto, of a coupler head pivotally mounted upon said stem, means for centralizing said stem with respect to the railway vehicle, and means for centralizing said head with respect to said stem, said means for centralizing said stem involving a plurality of levers having floating pivotal axes.

10. In a railway draft appliance, the combination with a coupler stem which is adapted to be connected to a railway vehicle so as to swing laterally with respect thereto, of a coupler head pivotally mounted on said stem, means for centralizing said head with respect to said stem, and means for centralizing said stem with respect to the railway vehicle, said last named means involving a spring mounted upon and extending in the direction of length of said stem, and a plurality of overlapping levers having spaced pivotal axes.

In testimony whereof we affix our signatures.

WILLIAM KELSO.
